UNITED STATES PATENT OFFICE.

JAMES S. REID, OF CLEVELAND, OHIO, ASSIGNOR TO THE NEWELL THOMPSON MFG. CO., OF CLEVELAND, OHIO, A CORPORATION OF OHIO.

DRUM AND BAND STRUCTURE.

Application filed September 7, 1926, Serial No. 134,066. Renewed June 11, 1927.

This invention relates to improvements in drum and band structures, such as are used, for example, in braking mechanism and shock absorber devices for motor vehicles.

5 The object of the present invention is to provide an improved drum and band structure in which either the drum or the band member is provided with a series of containers adapted for frictional engagement 10 with the other member, said containers being of softer metal than the member engaging therewith so that the wear resulting from said frictional engagement will be borne by said containers, which can be easily and 15 inexpensively replaced, when necessary. These containers are adapted to hold a suitable lubricant, so that all necessary parts of the structure will be easily and inexpensively maintained in a well lubricated condition.

20 Further objects of the invention are in part obvious and in part will appear more in detail hereinafter.

In the drawing, Fig. 1 is a vertical section view of a drum and band structure embodying my invention; Fig. 2 is a side elevation thereof, part being broken away and in section for clearness of illustration; Fig. 3 is a view similar to Fig. 1 and showing a modification; Fig. 4 is a detail sectional view showing a still further modification.

The structure illustrated in the drawing includes a metal drum 1, of any suitable size 25 and shape, and 2 represents a flexible metal band adapted for co-operation therewith. Such a structure is adapted for varied use, two particular uses thereof being in braking mechanism and in shock absorber devices 40 for motor vehicles. For purposes of illustration, the drum is shown as of cup-shape and the flexible metal band is shown as surrounding a major portion of the circumference of said drum.

45 Either the metal drum or the flexible metal band is provided with a series of suitable lubricant carrying containers, and in the embodiment illustrated in Fig. 1, the flexible metal band 2 is provided with a 50 series of closely spaced hollow rivets 3. These rivets extend inwardly from said band and are adapted for frictional engagement 55 with the metal drum 1, said rivets being of brass or other metal of softer composition than the metal of the drum 1, which may be

made of steel, for example. Therefore, the wear resulting from the frictional engagement of said rivets and the drum will be borne by said rivets, which may be easily and inexpensively replaced, when necessary. The chambers or cavities of said rivets are adapted to hold graphite or other suitable lubricant, so that all necessary parts of the structure are easily and inexpensively maintained in a proper lubricated condition.

The present drawings show the lubricant carrying containers arranged in two annular rows, but any other suitable spacing or arrangement may be employed, it being only necessary to provide a sufficient number of 70 containers and space them close enough together that proper frictional engagement can be had with the member co-operating therewith.

In the embodiment of the invention illustrated in Fig. 3, the metal drum 1^a, rather than the flexible metal band 2^a, is provided with the lubricant carrying containers. In this form of the invention said containers are simple cup-shaped member 6 which are partially pressed down with a snug fit into suitable apertures 7 in the metal drum, and which project outwardly from said drum a sufficient amount for frictional engagement with the flexible metal band. These receptacles, just as the hollow rivets 3, are adapted to be filled with lubricant and are likewise made of brass or other metal softer than the metal of the flexible band 2^a, so that they will bear the wearing effects of the frictional 90 engagement.

In the embodiment of the invention illustrated in Fig. 4, cup-shaped lubricant carrying containers 8 are employed, just as in Fig. 3, and are likewise mounted in the 95 metal drum 1^b, rather than in the flexible metal band 2^b. However, in Fig. 4 the metal of the drum surrounding the apertures 7^a, in which said containers seat, is bent upwardly in the form of annular flanges 8, is 100 clearly indicated in the drawing. Any suitable manner of securing or mounting the lubricant carrying containers in the metal drum or in the flexible metal band may be employed, the forms shown in the drawing, 105 being simply for purpose of illustration.

From the foregoing, it will be seen that I have provided a drum and band structure which is maintained in a well lubricated condition by lubricant carrying containers 110

which co-operate with either the drum or the band to provide the desired frictional engagement, and which containers are made of relatively soft metal so that the wear resulting from such frictional engagement will be borne thereby. When necessary, said containers may be easily and inexpensively replaced. The structure is therefore of exceedingly simple form, comprising a minimum number of parts, and is efficient and satisfactory in use.

What I claim is:

1. A structure of the character described, comprising a metal drum member, a metal band member, and lubricant receiving metal containers carried by one of said members and adapted for frictional engagement with the other of said members.
2. A structure of the character described, comprising a metal drum member, a metal band member, and lubricant receiving metal containers carried by one of said members and adapted for frictional engagement with the other of said members, said containers being softer metal than the member engaging therewith.
3. A structure of the character described,

comprising a metal drum member, a metal band member, and closely spaced lubricant receiving metal containers carried by one of said members and adapted for frictional engagement with the other of said members.

4. A structure of the character described, comprising a metal drum, a metal band, and lubricant receiving metal rivets mounted in said metal band and projecting therefrom for frictional engagement with said metal drum.

5. A structure of the character described, comprising a metal drum, a metal band, and lubricant receiving metal containers carried by said metal band and adapted for frictional engagement with said metal drum.

6. A structure of the character described, comprising a drum member, a band member, and lubricant receiving metal containers carried by one of said members and adapted for frictional engagement with the other of said members, the member thus engaged by said containers being of metal.

In testimony whereof I hereby affix my signature.

JAMES S. REID.
